UNITED STATES PATENT OFFICE

155,842

DESIGN FOR AN ELECTRIC GRIDDE

Raymond C. Sandin, Oak Park, Ill., assignor to
Hotpoint Inc., Chicago, Ill., a corporation of
New York

Application March 16, 1948, Serial No. 145,155

Term of patent 14 years

(Cl. D81—10)

To all whom it may concern:

Be it known, that I, Raymond C. Sandin, a citizen of the United States, residing at Oak Park, in the county of Cook, State of Illinois, have invented a new, original, and ornamental Design for an Electric Griddle, of which the following is a specification, reference being had to the accompanying drawing, forming a part thereof.

The accompanying drawing shows in the single figure a perspective view of an electric griddle embodying my new design.

The other side of the electric griddle, not shown, is substantially like the side shown; and the back thereof is substantially plain.

I claim:

The ornamental design for an electric griddle, substantially as shown and described.

RAYMOND C. SANDIN.
